UNITED STATES PATENT OFFICE.

GEORGE A. LEWIS AND ROBERT I. LEWIS, OF LYNN, MASSACHUSETTS.

PHOTOGRAPHIC APPARATUS.

1,427,750.

Specification of Letters Patent. Patented Aug. 29, 1922.

Application filed January 13, 1921. Serial No. 437,054.

To all whom it may concern:

Be it known that we, GEORGE A. LEWIS and ROBERT I. LEWIS, both citizens of the United States, residing at Lynn, in the county of Essex and Commonwealth of Massachusetts, have invented certain new and useful Improvements in Photographic Apparatus, of which the following is a specification.

10 Our invention relates to improvements in photographic apparatus used in the art of photo-engraving, and the reproduction of original photographs by commercial photographers. And more particularly it relates to the method and the device employed for the reproduction of photographs made in the first instance upon paper of rough, pebbled, dull, or grainy surface.

The objects of our invention are:

20 To provide a method by means of which it is possible to reproduce photographs in a perfect manner.

To provide for use in reproducing photographs a method which eliminates the oil 25 or grease heretofore used by photoengravers and commercial photographers.

To provide a method which after use leaves the original photograph in perfect condition.

30 To temporarily conceal the grain of an original photograph that it may be reproduced as a smooth surface.

To sharpen and brighten the lines of an original photograph which is to be reproduced.

To accentuate, what is known in the art, as the "detail" of the photograph to be reproduced.

40 To provide a method which insures a smooth surface for reproduction irrespective of the original copy.

And to secure other advantages and results some of which are evident from the following specification.

45 The above being among the objects of our invention, the same consists in the method herein described, and the steps of which are included in the appended claims, reference being had to the accompanying drawings, 50 which are illustrative of the method, and in which Figure 1 shows a front view of our

device. Figure 2 shows a cross sectional view of our device on the line AA in Figure 1. Figure 3 shows the detail of the working parts of the device used in our improved 55 method. Similar letters refer to similar parts throughout the various views.

In Figure 1 (B) shows the back of the body portion of our device which is box like in shape, (B') shows the bottom of our device, (B²) shows the side portions of our device. The top of said box portion is open at (B³) so as to receive the photograph or copy to be reproduced; the glass which is used in backing up the same, and the water 60 which is used in connection with our improved method. The front side of our body portion is of glass (C) firmly imbedded in a composition of wax in the holding frame (D), which is positioned about the lower 65 and two side portions of the front of our box like device. The bar (E) at the top of the said glass front is provided for the better protection of the glass C, and for the purposes of holding steadily and in position, 70 parallel to each other, the sides of the frame (D). The bottom (B') of our box like device is built on a bevel so as to form the pocket (C'). This bevel construction automatically positions the secondary or back- 75 ing up glass (C²) close, or adjacent, to the wax imbedded glass (C) at its base portion. The secondary glass front (C²) lies parallel to the wax imbedded glass front (C), 80 throughout its area when pressed against the same by action of the springs (F) which are positioned at the top of our box shaped device. The springs (F) are secured to the sides (B²) and extended from the point at 85 which they are so secured in the direction 90 of the open top (B³). Said springs (F) terminate in the hooks (F') which are for the purposes of holding the roll shaft (G) onto said springs. The holding roll (G') is positioned on the shaft (G), and is made from 95 rubber or other pliable material. This holding roll (G') by action of the springs (F) is pressed and firmly held against the secondary glass front (C²) so as to constantly insure an even pressure of the same 100 against the wax imbedded glass front (C).

In use we fill our box like device to within

an inch or so from the top with clear water. Then by raising the roll shaft (G) on the springs (F) we release the secondary glass front (C²), lift out said secondary glass 5 and position thereon the photograph which has previously been water soaked. When the secondary glass (C') and the holding roll (G') are returned to their first position the space between the secondary glass (C²) 10 and the imbedded glass front (C) is minimized by pressure of the controlling roll (G). It will be understood that the photograph to be reproduced is then between the secondary plate (C²) and the wax im- 15 bedded glass front (C).

Our improved method comprises the saturation in water of an original photograph, to be reproduced, and its immersion in a 20 quantity of water held in a container having a transparent side, the face of said photograph being held against said transparent side by parallel means at the back thereof, and the ordinary steps of photography then being followed while said photograph is so 25 immersed and so held face against said transparent side.

To those skilled in the art to which our invention appertains it is obvious that the method described is a radical change and 30 improvement over and above the methods heretofore known and used. Our method need not be followed except as specified in the claims, nor necessarily in the order named, and the method is therefore susceptible 35 of modification.

It will be understood that after the photograph has been reproduced it is dried, ordinarily by placing it between two blotting sheets. After being properly dried in a flat 40 position it may be mounted in any way desired. It is demonstrated that the use of our improved method leaves the photograph undamaged, a result highly desirable in the art of photoengraving or commercial photography. 45

Our improved method eliminates the use of oils, greases, and glycerine, which have heretofore been resorted to in attempting to accomplish the perfect results our method 50 insures, and also eliminates the inconveniences of evaporation and drying heretofore encountered.

It is clearly demonstrated that our improved method as described effectively eliminates 55 the grain and roughness of the original photograph, sharpens and brightens the lines thereof, accentuates the detail, insures better gradations, and on the whole is a tremendously marked improvement over the 60 methods and processes heretofore known or used.

Having thus described our invention we claim as new and desire to secure by Letters Patent of the United States.

1. A device of the kind described, comprising a box constructed to contain a liquid and having a front glass plate, a secondary glass plate for pressing a print against said front glass plate, said box being formed with a bottom which is inclined downwardly towards the front of the box to automatically position the bottom edge of the secondary glass plate in close relation to the front glass plate, and a pressing means at the top of the box for pressing the top edge of the secondary glass close to the front glass. 70 75

2. A device of the kind described, comprising a box constructed to contain a liquid and having a front glass plate, a secondary glass plate for pressing a print against said front glass plate, said box being formed with a bottom which is inclined downwardly toward the front of the box to automatically position the bottom edge of the secondary glass plate in close relation to the front glass plate, and a spring-pressed roller extending across the top of the box for pressing the top edge of the secondary glass close to the front glass. 80 85

3. A device of the kind described, comprising a box constructed to contain a liquid and having a front glass plate, a secondary glass plate for pressing a print against said front glass plate, said box being formed with a bottom which is inclined downwardly toward the front of the box to automatically position the bottom edge of the secondary glass plate in close relation to the front glass plate, a roller extending across the top of the box, and springs secured to the outside of the box and engaging the ends of said roller to engage the same against the secondary glass and press it close to the front glass. 90 95 100

4. A device of the kind described, comprising a box constructed to contain a liquid and having a front glass plate, a secondary glass plate for pressing a print against said front glass plate, said box being formed with a bottom which is inclined downwardly toward the front of the box to automatically position the bottom edge of the secondary glass plate in close relation to the front glass plate, a roller extending across the top of the box, and springs secured to the outside of the box and engaging the ends of said roller to engage the same against the secondary glass and press it close to the front glass, said springs being formed with bent upper ends to support said roller in a non-pressing position to permit the insertion of 110 115 120 the secondary glass.

5. A device of the kind described, comprising a box constructed to contain a liquid and having a front glass plate, a secondary glass plate for pressing a print against said front glass plate, said box being formed with a bottom which is inclined downwardly towards the front of the box to automatically 125

5 cally position the bottom edge of the secondary glass plate in close relation to the front glass plate, and a pressing means at the top of the box for pressing the top edge of the secondary glass close to the front glass and also to form a support for the pressing means in a non-pressing position to permit the insertion of the secondary glass.

In testimony whereof we affix our signatures in the presence of two witnesses.

GEORGE A. LEWIS.
ROBERT I. LEWIS.
